UNITED STATES PATENT OFFICE.

CHARLES RIPPON WEATHERHOGG, OF FORT WAYNE, INDIANA.

DESIGN FOR A LAMP-POST.

41,518.

Specification for Design. Patented June 27, 1911.

Application filed March 20, 1911. Serial No. 615,798. Term of patent 14 years.

To all whom it may concern:

Be it known that I, CHARLES RIPPON WEATHERHOGG, a citizen of the United States of America, residing at No. 334 East Berry street, in the city of Fort Wayne, county of Allen, and State of Indiana, have invented a new, original, and ornamental Design for a Lamp-Post, of which the following is a specification, reference being had to the accompanying drawing, forming part thereof.

The figure is a plan view of a lamp post, showing my new design.

I claim:

The ornamental design for a lamp post, as shown.

CHARLES RIPPON WEATHERHOGG.

Witnesses:

EVA B. FINAN,
J. M. BERGHOFF.
